UNITED STATES PATENT OFFICE.

HENRY M. RUDEN, OF NEW HAVEN, CONNECTICUT.

ENGRAVING-MACHINE.

SPECIFICATION forming part of Letters Patent No. 629,210, dated July 18, 1899.

Application filed October 20, 1898. Serial No. 694,132. (No model.)

To all whom it may concern:

Be it known that I, HENRY M. RUDEN, of New Haven, in the county of New Haven and State of Connecticut, have invented a new Im-

5 provement in Machines for Engraving, Milling, &c.; and I do hereby declare the following, when taken in connection with the accompanying drawings and the letters of reference marked thereon, to be a full, clear, and 10 exact description of the same, and which said drawings constitute part of this specification, and represent, in—

Figure 1, a side view, partially in section, of a machine embodying my invention; Fig. 15 2, a top or plan view of the same; Fig. 3, an end view; Fig. 4, a sectional view on the line 4 4, looking in the direction of the arrow 4 of Fig. 1; Fig. 5, a sectional view on the line 5 5 of Fig. 2.

20 This invention relates to an improvement in machines for engraving, milling, modeling, die-sinking, &c., in which a pattern is employed containing the design or shape of the article to be milled, engraved, or otherwise 25 formed or ornamented, and which pattern is reproduced either of the same size or larger or smaller, as may be desired.

The object of this invention is a simple construction and arrangement of mechanism 30 whereby the movement of the pointer or index-finger used to trace the design or form of the pattern will be positively duplicated by the milling or engraving tool, so as to reproduce that pattern; and it consists in the construction and arrangement of parts, as will 35 be hereinafter described, and particularly recited in the claims.

The bed A is of the desired length and width and adapted to be conveniently supported. At each end of the bed is fixed an upright bracket B. Near the top of each bracket is a horizontal trunnion-bearing slot b, and below this and parallel with it is a horizontal yoke-clamping slot c. In each trunnion-bearing slot b is a trunnion-bearing slide b', formed with an outwardly-projecting arm d, through which a screw D extends, each of the said screws having a bearing in a lug d', formed near one edge of the brackets B. 45 Through the trunnion-bearing slides b' extend trunnions E, which project from the re-

spective ends of a yoke, which comprises a long central shaft-bearing F and chuck-carriers F' F''. At each end of the yoke is attached a plate G, depending downward at 55 right angles to the chuck-carriers, and each plate is formed on its inner face with a lug g, through which screws g' extend upward into the chuck-carrier, whereby the plates are rigidly connected with the yoke. Each plate is 60 formed with a segmental lug G', projecting outward to the inner face of the brackets B, and in each of these lugs is a segmental slot h, forming the arc of a circle of which the center of the trunnion is the center, and these 65 slots h register with the horizontal slots c in the bracket, so that these arms and the brackets may be connected by a set-screw h', which extends through the segmental slot and through the slot c in the bracket, and so that 70 while the yoke may be free to be rocked on its trunnions it may also be locked in any desired position. In each chuck-holder is mounted a chuck, the pattern-holding chuck I being formed with a long hollow stem J, 75 carrying at its lower end a bevel-pinion K, which meshes into a bevel-pinion K', mounted on one end of the shaft L in the bearing F. At the opposite end of the said shaft L is a bevel-pinion K'', meshing into a pinion K'', 80 formed at the lower end of the work-holding chuck I', and so that the rotation of the pattern-chuck will cause the work-holding chuck to be rotated in the same direction.

On opposite sides of the bed are mounted 85 vertical brackets M. N. The inner face of the bracket N is formed with a wide undercut projection N', forming a vertical guide for a bridge O, which on the side toward the bracket N is formed with a wide undercut 90 groove O', corresponding to the projection N', with which it may be interlocked by the set-screw e, which is also employed to take up wear. The said bracket is also formed with a clearance-slot P, into which a lug P', formed 95 on the side of the bridge, extends, the said lug having a vertical hole threaded for the reception of a set-screw Q, which is mounted on the base, beneath which it is provided with an operating-head Q', and so that by 100 turning the screw the bridge may be raised or lowered. On the opposite side the bridge

is formed with a hole or perforation P^2 for the reception of a screw, which extends through a slot P^3 in the bracket M , and so that that side of the bridge may be clamped to the bracket M . In the center of this bridge upon a stud R are mounted two long links S S' of a lazy-tongs or pantograph, and the short links S^2 , S^3 , S' , and S^3 are connected with the long links S S' and are respectively connected with 5 rotatable posts T T' , projecting upward from carriages T^2 T^3 , which are longitudinally guided in undercut grooves U , formed in opposite ends of the bridge. To the upper end of the post T' is pivotally connected an arm V , which projects outward over the pattern-holding chuck I , and at its end carries an index or pointer W . To the post T a corresponding arm V' is pivoted, which at its outer end is adapted to receive a milling or engraving tool W' , which may be operated through a flexible connection X in the usual manner. These arms are connected by rods Y Y' , which are respectively mounted and guided in bearings formed at the upper edges of the arms, 10 and at their inner ends are bifurcated and the ends of one arm secured to the sides and the ends of the other arm secured to the top and bottom of a ball Y^2 , forming a gimbal-joint. Also connected to the sides of the ball is a yoke h , formed with a depending pin h' , which extends through a slide m , which is mounted in transverse guides n n' , which are held above the bridge by supports o mounted thereon.

15 The pattern to be reproduced is placed in the pattern-holding chuck I , and if it be formed with a shank or stem—like a door-knob, for instance—the stem may pass into the hollow stem J of the chuck. This pattern is 20 clamped in the chuck in any desired manner. The piece of metal to be milled, engraved, or otherwise operated upon is similarly fixed in the work-holding chuck I' . The index-finger or pointer W is then pressed downward onto 25 the surface of the pattern in the chuck, and in thus depressing the index-finger the inner end of the rod Y' is lifted, which lifts the inner end of the rod Y , and hence depresses the working tool W' , and as the arm V is 30 drawn outward it moves the links S and S' , which also force the arm V' outward to a corresponding distance. If the arm V be turned to the right or left, the arm V' will be correspondingly turned, and the stem k being held 35 by the carriage M in the guides n will always keep the ends of the rods Y Y' midway between the arms V V' , said arms being free to rock upon the upper ends of the posts T T' , which in turn rotate in the carriages T^2 T^3 . 40 The chucks are readily rotated by hand, and the rotation of the pattern-chuck I imparts a corresponding rotation to the work-holding chuck I' through the bevel-gears and rock-shaft, as already described. By means of the 45 adjusting-screw D the bearing for the chuck-carrying yoke may be moved from side to side, and by loosening the end of the set-

screw h' the yoke itself may be rocked so as to incline the chuck I in either direction. The bridge, and hence the arms and other mechanism carried thereby, may be raised or lowered through the adjusting-screw Q , whereby the horizontal position of the arms V V' may be adjusted.

Having fully described my invention, what I claim as new, and desire to secure by Letters Patent, is—

1. The combination with a horizontal bed of two brackets, one at each end of the bed and in each of which a chuck-carrying yoke is pivotally mounted, chucks supported in carriers at opposite ends of the yoke, and connected by a shaft and gearing, whereby the movement of one is imparted to the other, a bridge over said bed and vertically adjustable with relation thereto, and two arms pivotally mounted above said bridge, and coupled together whereby the movement of one imparts a corresponding movement to the other, one of said arms adapted to carry an operating-tool, substantially as described.

2. The combination with a horizontal bed of a bracket mounted at each end thereof, and each formed with a transverse trunnion-bearing slot, a trunnion-bearing in said slot, a yoke formed at opposite ends with trunnions extending into said bearings, said yoke provided at opposite ends with chuck-holders, chucks in said holders and connected with each other, whereby movement of one is imparted to the other, a bridge over said bed, and vertically adjustable with relation thereto, lazy-tongs links pivotally mounted on said bridge, and engaging at opposite ends with posts which are longitudinally guided on the bridge, arms pivotally mounted at the upper ends of said posts, rods mounted in the upper ends of said arms and coupled together by a gimbal-joint, a transversely-movable guide below said joint, and a pin depending from the joint into said guide, one of said arms carrying an operating-tool, substantially as described.

3. The combination with a horizontal bed, of a vertically-arranged bracket at the opposite ends thereof, said brackets formed near their upper ends with transverse trunnion-bearing slots, and with yoke-clamping slots parallel with the trunnion-bearing slots, a trunnion-bearing in said trunnion-bearing slots, a yoke provided at opposite ends with trunnions extending into said bearings, said yokes having downwardly-depending plates at their respective ends, a segmental slot in each of said plates, and means for clamping said plates to the brackets, chucks mounted in the respective ends of said yoke, and connections between them, whereby movement of one is imparted to the other, brackets secured to the opposite sides of said bed, a bridge extending across said bed and supported by said brackets with which it is adjustably connected, two carriers longitudinally movable in the upper surface of said

bridge, and an upwardly-extending post mounted in each carrier, lazy-tongs connecting said posts and pivotally mounted on the upper face of said bridge, arms pivotally mounted in the upper ends of said posts, and rods mounted in the upper ends of said arms and flexibly connected together, and a pin depending from the center of the connection between the rods into a slide guided for trans-

verse movement across said bridge, substantially as described.

In testimony whereof I have signed this specification in the presence of two subscribing witnesses.

HENRY M. RUDEN.
